SYMMETRICAL BRIDGE FOR REDUCING HUM
IN VACUUM TUBES

Julius J. Hupert, River Forest, Ill., assignor to A. R. F. Products, Inc., River Forest, Ill., a corporation of Illinois

Application July 20, 1953, Serial No. 369,061

13 Claims. (Cl. 315—105)

This invention is concerned generally with the elimination of hum from amplifiers, and is concerned more particularly with a circuit for reducing line frequency hum in indirectly heated, sensitive vacuum tube stages.

When low level electrical potentials are amplified to substantial levels, hum elimination becomes a major problem. The most difficult type of hum to eliminate is that originating in the A. C. heater supply. Hum generally can be satisfactorily eliminated from plate and grid supply sources by adequate filtering.

A major source of hum and the source which produces the dominating hum effect in sensitive amplifiers and modulators using conventional receiving type tubes is the hum caused by leakage between the cathode and the heater in indirectly heated tubes. The present invention is concerned with the elimination or reduction of hum produced from this source.

An object of this invention is to provide means for reducing hum in indirectly heated, sensitive vacuum tube stages.

Another object of this invention is to provide means for reducing hum caused by leakage between cathode and heater in circuits employing vacuum tubes having indirectly heated cathodes.

A more specific object of this invention is to provide a bridge circuit for reducing hum in circuits employing vacuum tubes having indirectly heated cathodes.

Yet another specific object of this invention is to provide a bridge circuit for reducing hum in circuits employing vacuum tubes having indirectly heated cathodes wherein the balance of the bridge is not critical and is adjustable.

Still another object of this invention is to provide a circuit for reducing hum in amplifying circuits employing vacuum tubes having indirectly heated cathodes in which the cathode has a bias impressed thereon.

A further object of the invention is to provide a bridge circuit for reducing hum in amplification circuits employing vacuum tubes having indirectly heated cathodes, the cathode having a bias impressed thereon and being connected directly to the bridge circuit.

Other and further objects and advantages of the present invention will be apparent from the following description when taken in connection with the accompanying drawings wherein:

Fig. 1 is a circuit diagram illustrating the principles of my invention;

Fig. 2 is a bridge circuit diagram equivalent to the circuit of Fig. 1;

Fig. 3 is an equivalent circuit symmetrical bridge for circuit equations;

Fig. 4 is a simplified equivalent circuit for nonlinear leakage;

Fig. 5 is a circuit diagram incorporating the principles of my invention for testing signal-to-hum ratio; and

Fig. 6 illustrates the statistical distribution of a number of tubes tested for signal-to-hum ratio in the circuit of Fig. 5.

2

Leakage between cathode and heater is most often caused by contamination of the heater-cathode space and bordering surfaces by the emitting material. This physical character of the leakage generally brings about leakage of a nonlinear character. However, the leakage may be linear. It may be localized or distributed, and it may be symmetrical or asymmetrical (uni-directional).

Grounding of one side of the heater transformer winding has proved unfeasible as a means for reducing hum. If cathode return bias (self-bias) is used, spurious line voltage is injected into the grid circuit of the tube as a result of voltage drop across the cathode return resistor caused by the leakage current between heater and cathode. The cathode return resistor might be bypassed but in general the capacitor required is too large to fit in the space available and is not economical. The provision of fixed bias is unsatisfactory in view of the normal variations to be found among vacuum tubes. There is no automatic compensation, and a fixed bias suitable for one tube sample may not work for the next. Furthermore, fixed bias often leads to difficult component choice or unnecessary design complication.

A grounded center tap on the heater transformer offers some degree of hum reduction, and is the expedient commonly adopted in practice. This halves the electromotive force causing the leakage current and eliminates spurious cathode current between the center of the heater and the cathode. However, this expedient is not satisfactory where extreme immunity from hum is desired due to the effect of leakage capacitances between ground and the heater transformer windings. These capacitances are generally unequal, thus preventing full symmetrizing, and are largely unpredictable.

I have found that the circuit shown in Fig. 1 substantially eliminates hum without possessing any of the drawbacks of the prior art. This circuit is illustrated with a vacuum tube 10 which may be of the triode type, or any other type having at least a plate 12, control grid 14, an indirectly heated cathode 16, and a heater 18. The opposite ends of the heater or filament 18 are connected by suitable wires 20 and 22 to the opposite ends 24 of the filament winding 26 of the transformer 28. It will be understood that the transformer 28 may incorporate additional windings (not shown) according to the usual practice in radio power transformers. A pair of capacitors 30, labeled C_s on the drawings, is connected between the ends 24, 24 of the heater winding 26, and the junction between these two capacitors is grounded as at 32. A resistor 34 is connected between the winding ends 24 in parallel with the series arranged capacitors 30 and is provided with a sliding tap 36. The resistance to the left of the tap is indicated at R_1 while the resistance to the right of the tap is indicated at R_2 .

A resistor 38 of high value and indicated at r_{c2} on the drawings is connected to the sliding tap 36, and is in turn connected by a wire 40 to the cathode 16 and to a wire 42. The wire 42 is connected to a cathode return resistor 44, also labeled as r_{c1} . Leakage resistances between the heater 18 and cathode 16 are indicated at 1, 2, and 3.

It is to be noted that the connection between the bridge and the cathode is not at ground potential but is somewhat above ground potential, as determined by the cathode return resistor 44. This circuit arrangement imposes the correct enforced potential on the cathode at all times without interference of hum reduction, as will be more fully described below.

The capacitors C_s and the resistors R_1 and R_2 form a bridge, and it is apparent that when the bridge is balanced there will be no leakage current through the resistors r_{c1} and r_{c2} . The capacitors in practice are low tolerance paper condensers, and also include stray wiring capacitances. Thus, it is apparent that in general they

will not be exactly equal, and that for balance of the bridge the resistors R_1 and R_2 will be unequal.

Critical bridge adjustment is undesirable and hence an approximation of the leakage current through the cathode resistors with the bridge unbalanced is in order as giving an indication of how critical the adjustment is. Calling the cathode resistance R_c and assuming $R_c = r_{c2}$, then $r_{c2} = 0$. Referring to the equivalent circuit of Fig. 2, the equivalent leakage resistance between cathode and heater is indicated at R_x (assumed linear and capacitive). This resistance can be transferred to one side of the bridge for purposes of analysis. The transfer of the leakage resistance to one side of the bridge is indicated in the equivalent circuit of Figure 3. In Figure 3, R_b corresponds to R_1 and R_2 in Figures 1 and 2. By mesh analysis we have, in complex numbers:

$$\begin{aligned} e &= i_1(2Z_1) + i_2 \cdot O + i_3 Z_1 \\ E &= i_1 \cdot O + i_2(A + R_b) + i_3(-R_b) \\ O &= i_1 Z_1 + i_2(-R_b) + i_3(Z_1 + R_b + R_c) \end{aligned}$$

Hence, the current through R_c ,

$$i_3 = e \frac{1}{(Z_1 + 2R_c) \left(1 + \frac{1}{1 + R_b/R_x} \right) + \frac{2R_x}{R_x/R_b + 1}}$$

In the above equation Z_1 is imaginary if it represents a capacity.

In a conventional hum reducing circuit wherein the only compensation comprises grounding the center tap of the heater transformer winding, the current i_3 flowing through the cathode resistance R_c is:

$$i_3 = \frac{e}{2R_x}$$

If the resistance R_b is made very large, i. e., $R_b \rightarrow \infty$, $|Z_1| \gg R_c$, then

$$|i_3| \rightarrow \left| \frac{e}{2R_x + Z_1} \right|$$

Thus, it readily may be seen that the cathode leakage current is greatly reduced from that present in conventional circuits when the bridge resistance, $R_b = R_1 + R_2$, is very large and when $|Z_1|$ is very large.

Also, when $R_b/R_x \rightarrow 0$, $|i_3| \rightarrow 0$. Therefore, the ratio R_b/R_x desirably should be held as small as possible.

For example, when $R_b = 0.1R_x$,

$$|i_3| = \left| \frac{e}{19Z_1 + 2R_x} \right|$$

This means that $|i_3|$ is much less than i_3 , particularly when $|Z_1|$ is of the same order of magnitude as R_x .

If $R_b = R_x$, then

$$|i_3| = \frac{e}{3Z_1 + 2R_x}$$

For $|Z_1|$ of the same order as R_x , there is a few decibels improvement in comparison with i_3 . R_b should be made as low and $|Z_1|$ as high as other design conditions permit.

A simplified equivalent circuit is shown in Fig. 4 for considering the effect of leakage of a nonlinear character. Assuming that:

(1) The bridge is balanced (R_b equal).

(2) R_c and the impedance between ground and the "equivalent ground point" on the heater are negligible compared to the nonlinear leakage impedance, i. e., the leakage impedance controls the current through R_c .

(3) Uniform linear potential distribution across a heater of negligible impedance and finite size.

(4) Leakage current density i is nonlinear (with respect to the potential e causing it) and is of continuous, uneven, asymmetrical distribution.

i is defined as current in microamperes per unit of heater length.

e is the potential of a cathode point with respect to ground and is variable with time and position.

Therefore, $i = f(e, h)$

$e = \phi(t, h)$ namely

$$e = \frac{E}{H} \cos \omega t$$

Thus

$$i = f\left(\frac{E}{H} \cos \omega t, h\right)$$

$$I(t) = \int_{-\frac{H}{2}}^{\frac{H}{2}} idh = \int_{-\frac{H}{2}}^{\frac{H}{2}} f\left(\frac{E}{H} \cos \omega t, h\right) dh$$

Fourier analysis of the periodic function of time, $I(t)$, reveals values of harmonics.

By Maclaurin's theorem:

$$i = a_0(h) + a_1(h)e + a_2(h)e^2 + \cdots + \sum_{n=3}^{\infty} a_n(h)e^n$$

where $a_n(h)$ are functions of h such that

$$a_n(h) = \frac{1}{n!} \left[\frac{\partial^n f(e, h)}{\partial e^n} \right]_{e=0}$$

Hence:

$$I(t) = \sum_{n=0}^{\infty} \int_{-\frac{H}{2}}^{\frac{H}{2}} a_n(h) \frac{E^n}{H^n} h^n \cos^n \omega t dh$$

$$= \sum_{n=0}^{\infty} \frac{E^n}{H^n} \cos^n \omega t \int_{-\frac{H}{2}}^{\frac{H}{2}} a_n(h) h^n dh$$

For the case of step-wise distributed "S" nonlinear leakage points, the current-time function

$$I(t) = \sum_{n=0}^{\infty} \frac{E^n}{H^n} \cos^n \omega t \sum_{p=1}^{2^n} a_n(p) h(p)$$

where $a_n(p)$ and $h(p)$ are "point set" functions of p , denoting sequential number of any leakage position.

For the case of evenly distributed nonlinearity:

$$i = f(e)$$

$$a_n = \left[\frac{1}{n!} \frac{d^n f}{d e^n} \right]_{e=0}$$

$$I(t) = \sum_{n=0}^{\infty} \frac{E^n}{H^n} a_n \cos \omega t \int_{-\frac{H}{2}}^{\frac{H}{2}} h^n dh$$

$$= \sum_{n=0}^{\infty} \frac{E^n}{H^n} a_n \frac{H^{n+1} - (-H)^{n+1}}{2^{n+1}(n+1)} \cos^n \omega t$$

for n —odd, $I(t) = 0$

for n —even,

$$I(t) = \sum_{n=2,4,6,\text{etc.}} \frac{E^n H^{n+1}}{2^n (n+1)} a_n \cos^n \omega t$$

From the foregoing, it may be seen that if the nonlinear leakage is distributed uniformly only even harmonics will be noticed in the hum spectrum. It easily will be noticed that this also is true for uneven, but symmetrical distribution.

The bridge circuit shown and described heretofore substantially eliminates the fundamental component, which is the major component, but cannot eliminate the harmonic components as long as the resistance R_b is linear. Residual hum after the balancing of the bridge depends on the extent of the nonlinearity. In order to remove the nonlinearity effect, an additional bias between cathode and heater may be desirable.

The hum reducing bridge circuit herein disclosed has been tested experimentally on a large number of tube

samples. Conventional circuits were found experimentally to give widely divergent results as to signal to hum ratio with successive tube samples. However, the bridge circuit herein shown and described gave remarkably consistent results.

The test circuit is shown in Fig. 5 and is similar to the circuit of Fig. 1 with the addition of an audio frequency voltage from any suitable source 46. The tube 19 used was 6AH6 reactor tube. The capacitors 30 each were 0.5 microfarad and the resistor 34 was 5000 ohms. The cathode return resistor 44 was 100 ohms and the tap resistor 38 was 100,000 ohms. One hundred tubes were tested with a 60 cycle per second heater voltage and with a 1000 cycle per second heater voltage.

As may be seen in Fig. 6, with a 60 C. P. S. heater voltage all of the tubes produced a signal to noise ratio of between 56 and 64 db, the great majority falling between 60 and 63 db. With a 1000 C. P. S. heater voltage, all of the tubes produced a signal to noise ratio of between 57 and 62 db, most of them being between 59 and 62 db.

The bridge circuit herein shown and described largely eliminates hum from indirectly heated cathode type vacuum tube stages. The circuit is easily balanced and is not critical in balance. The circuit is economical and produces remarkably uniform results from one tube sample to another. Most particularly, the hum caused by leakage due to contamination of the heater cathode space is largely eliminated, and this hum has heretofore been the most troublesome encountered with conventional receiving type vacuum tubes.

The specific example shown and described is illustrative only, and the invention will be understood as including all that which falls within the spirit and scope of the appended claims.

I claim:

1. A hum reducing circuit for use with tubes having a cathode and a separate heater therefor, comprising a source of pulsating current for energizing the separate heater, a pair of capacitors series connected across said source, resistance means connected across said source in parallel with the pair of capacitors, a tap on said resistance means, a cathode return resistor connected between the cathode and the junction of said capacitors, and impedance means connected between said cathode and said tap to provide a relatively low impedance in parallel with the leakage impedance between said cathode and said heater and to provide a relatively high impedance in series with said cathode resistor.

2. A hum reducing circuit for use with tubes having a cathode and a separate heater therefor, comprising a source of pulsating current for energizing the separate heater, a pair of capacitors series connected across said source, resistance means connected across said source in parallel with said pair of capacitors, an adjustable tap on said resistance means, a second resistance means connecting said tap to the cathode, and a cathode return resistor connected between the cathode and the junction of said capacitors.

3. A hum reducing circuit for use with tubes having a cathode and a separate heater therefor, and including a source of alternating current for energizing the separate heater, a pair of capacitors series connected across said source, the junction between said capacitors being grounded, resistance means connected across said source in parallel with the pair of capacitors, an adjustable tap on said resistance means, a cathode return resistor connecting the cathode to ground, and an ungrounded impedance means connected between said cathode and said tap to provide a relatively low impedance in parallel with the leakage impedance between said cathode and said heater and to provide a relatively high impedance in series with said cathode resistor.

4. A hum reducing circuit for use with vacuum tubes

having a cathode and a separate heater therefor, and including a source of alternating current for energizing the separate vacuum tube heater, a pair of capacitors series connected across said source, the junction between

5 said capacitors being grounded, resistance means connected across said source in parallel with the pair of capacitors, an adjustable tap on said resistance means, ungrounded resistance means connecting said tap to the vacuum tube cathode, and a cathode return resistor connecting the cathode to ground.

10 5. A hum reducing circuit for use with vacuum tubes having a cathode and a separate cathode heater comprising a source of alternating current for energizing the separate cathode heater, a pair of capacitors series connected across said source, means grounding the junction

15 between said capacitors, resistance means connected across said source in parallel with said capacitors, an adjustable tap on said resistance means, a relatively large resistor connecting said tap to the vacuum tube cathode, and a relatively very small cathode return resistor connecting the cathode to ground.

20 6. A hum reducing circuit for use with vacuum tubes having a cathode and a separate cathode heater comprising a source of alternating current for energizing the separate cathode heater, a pair of capacitors series connected across said source, means grounding the junction

25 between said capacitors, resistance means connected across said source in parallel with said capacitors, an adjustable tap on said resistance means, an ungrounded resistor connecting said tap to the vacuum tube cathode, and a cathode return resistor connecting the cathode to ground, said ungrounded resistor being substantially smaller than the leakage resistance between said cathode and said heater and being substantially larger than said 30 cathode return resistor.

35 7. A hum reducing circuit for use with vacuum tubes having a cathode and a separate cathode heater comprising a source of alternating current for energizing the separate cathode heater, a pair of capacitors series connected across said source, means grounding the junction

40 between said capacitors, resistance means connected across said source in parallel with said capacitors, an adjustable tap on said resistance means, a relatively large resistor connecting said tap to the vacuum tube cathode,

45 and a relatively very small cathode return resistor connecting the cathode to ground, said connecting resistor being on the order of one thousand times the value of the cathode return resistor.

50 8. A hum reducing circuit for use with vacuum tubes having a cathode and a separate cathode heater and comprising a source of alternating current of a predetermined frequency for energizing the separate cathode heater, impedance means connected across said source and having an intermediate point grounded, said impedance means

55 having a relatively very high impedance at said predetermined frequency, resistance means connected across said source and of relatively very high resistance, a tap on said resistance means, a resistor connecting said tap to the vacuum tube cathode, and a resistor of relatively

60 very low resistance interconnecting said cathode and ground.

9. A hum reducing circuit for use with vacuum tubes having a cathode and a separate cathode heater and comprising a source of alternating current of a predetermined frequency for energizing the separate cathode heater, capacitance means connected across said source and having an intermediate point grounded, said capacitance means having a relatively very high reactance at said predetermined frequency, resistance means connected across said source and of relatively very high resistance, a tap on said resistance means, a resistor connecting said tap to the vacuum tube cathode, and a resistor of relatively very low resistance connecting said cathode to ground.

75 10. A hum reducing circuit for vacuum tubes having

a cathode and a separate heater therefor and comprising a source of alternating current for energizing the separate heater, impedance means connected across said source and having an intermediate point grounded, resistance means connected across said source and having a resistance which is small relative to the leakage resistance between the vacuum tube heater and cathode, a tap on said resistance means, means connecting said tap to the vacuum tube cathode, and a resistor connecting said cathode to ground.

11. A hum reducing circuit for use with tubes having a cathode and a separate heater therefor, comprising a source of pulsating current for energizing the separate heater, a first impedance connected across said current source, a second impedance connected in parallel with said first impedance, a movable tap on said second impedance, a third impedance connected between said movable tap and said cathode, and a fourth impedance connected between said cathode and an intermediate point on said first impedance, said third impedance being small compared to the leakage impedance between said cathode and said heater and being large compared to said fourth impedance.

12. A hum reducing circuit for use with tubes having a cathode and a separate heater therefor, comprising a source of pulsating current for energizing the separate heater, capacitance means connected across said source, a first impedance means connected across said source in parallel with said capacitance means, a movable tap on

5 said first impedance means, a second impedance means interconnecting said movable tap and said cathode, and a third impedance means interconnecting said cathode and an intermediate point on said capacitance means, said second impedance being small compared to the leakage impedance between said cathode and said heater and being large compared to said third impedance.

13. A hum reducing circuit for use with tubes having a cathode and a separate heater therefor, comprising a 10 source of pulsating current for energizing the separate heater, capacitance means connected across said source, a first resistance connected in parallel with said capacitance, said first resistance having a movable tap thereon, a second resistance interconnecting said movable tap and said cathode, and a third resistance interconnecting said cathode and an intermediate point on said capacitance, said second resistance being small compared to the leakage resistance between said cathode and said heater and being large compared to said third resistance.
